AUTOMATIC ARMS

Arturo Bardelli, Rome, Italy

Application October 3, 1956, Serial No. 613,747

Claims priority, application Italy October 8, 1955

1 Claim. (Cl. 89—190)

This invention relates to a semi-automatic rifle and refers more particularly to a gas-operated, trigger-fired, semi-automatic rifle.

It is a known fact that automatic arms always comprise delicate and complicated components which in most cases require machining to an extremely high degree of precision. The complicated and large number of parts therefore often introduce considerable maintenance and training difficulties.

An object of the present invention therefore is to provide certain improvements in essential firing mechanisms with a view toward insuring an easier construction and a more reliable operation of the entire rifle.

Still another object resides in the provision of integrally forming smaller essential firing parts with other parts of the mechanism so that the total number of operating parts is reduced and the overall general structure of the firing mechanism is simplified.

In the attainment of the aforesaid objectives, the inventive concept of the present invention may be realized through the provisions of forming the firing pin integrally with the breechblock mechanism and of forming the extractor and the ejector in such a manner that they become part of the breechblock-lock.

Other advantages of the present invention will be more clearly understood by referring to the accompanying drawings taken in conjunction with the following description which represents a non-limiting example of one preferred embodiment of the invention.

In the drawing:

Figure 1 is a longitudinal section of the firearm showing the breechblock in the battery position after firing.

Figure 2 is a longitudinal section showing the breechblock in a firing position.

Figure 3 is an enlarged longitudinal section of the breechblock.

Figure 4 is an enlarged longitudinal section showing the head of the breechblock at one end of the recoil stroke.

Referring now to the drawings in greater detail, reference numeral 10 indicates a breechblock mechanism and like reference numerals indicate like parts.

The breechblock 10 is constituted of a pivot 11 disposed intermediate an extractor 12 and an ejector 13. A locking bar 15 provided with two projections 16 and 17, one at each end thereof, is mounted on the breechblock 10 by means of another pivot 14 disposed at one end of the locking bar 15. The projection 16 maintains the breechblock 10 in the battery position after firing as shown in Figure 1. Projection 17, which is a part of hub 18a pivoted about pivot 18, oversets together with the locking bar 15 during the movement of the breechblock and strikes the ejector 13 when the breechblock 10 is in a firing position as shown in Figure 2 and causes the cartridge (not shown) to be ejected.

The free end 18a of the locking bar 15 is pivoted freely on a pivot 18 which slides into a groove 19 in the receiver 20 by means of two axial projections (not shown) formed

2

on each side of the pivot 18. The groove 19 causes the pivot 18 to be forced, and consequently the free ends 18a of the locking bar 15, to move vertically downward and then upward by the effect of gas pressure when the breechblock 10 moves backward and forward, respectively, to feed another shell into the chamber.

As shown in Figure 1, the breechblock 10 is prevented from moving backward as long as the locking bar 15 is maintained in a horizontal position such that pivots 14 and 18 are aligned along the axis of the arm, and pivot 18 is engaged in groove 19.

A piston 23 pushes a yoke 24 backward when it is subjected to the pressure of the gases flowing through a duct 22. The piston 23 bears upon the projection 16 of the locking bar 15 as shown in Figure 1 while the pivot 18 moves vertically downward until the position of the locking bar 15 is reversed as shown in Figure 2. Thus, pivot 18 engaged in groove 19 moves first downward and then upward until the projection 17 strikes the ejector 13 and causes the spent cartridge case to be ejected (Figure 2). In the meantime the breechblock 10 is engaged by the trigger sear 25, and the spring 26 remains fully loaded (Figure 2).

By pulling the trigger the two levers 25—25' are operated simultaneously, the breechblock is released from the yokes 27 and 27' simultaneously, and the spring 26 pushes the breechblock 10 forward. Lever 25 moves immediately back into inoperative position, being loaded by a spring not shown in the drawing. Lever 25' comes back into inoperative position only when the trigger is released in order to prevent the breechblock from being retained by said lever 25'. In firearms in which the breechblock is fastened to the striker, a shot is fired by pulling the trigger. If when cocking the firearm again care is not taken to bring the breechblock again into engagement with lever 25, spring 26 causes the said breechblock to close and a shot to be fired. This inconvenience is prevented by the action of said lever 25'. If in the meanwhile, the breechblock has already extracted a cartridge, but is stopped by lever 25, the cartridge can be easily removed. If the operator has taken no care to bring the breechblock into engagement with lever 25' the cartridge is not extracted from the reservoir. The springs which act on lever 25 and 25' are spiral springs and are not shown in the drawings. Simultaneously, with the action following the pulling of the trigger pivot 18 of the locking bar 15 engaged in groove 19 moves vertically down and up and causes the locking bar 15 to return to its initial position (Figure 1) while the breechblock 10 pushes the fresh shell into the chamber and fires it.

In order that the extractor 12 performs in such manner that insures perfect, automatic operation of the firearm, a tooth 12' disposed at one end of the extractor 12 must (a) hook the cartridge case easily, (b) hold the case firmly during extraction, (c) release the case at the time of ejection, (d) remain rigid to prevent any premature contact with a firing pin 28 while the cartridge is shifted from a magazine (not shown) and into the chamber.

As shown in Figures 3 and 4, the extractor 12 is essentially a lever which has its fulcrum disposed in pivot 11 and is mounted thereon in such manner that a degree of free play may be effected by the extractor when the breechblock is in either the rest or firing position.

A smooth projection 12'' is integrally formed to the opposite end of the extractor 12 and rests frictionally upon a hub 32 of the locking bar 15 adjacent the pivot 14 during either forward or backward movement of the breechblock 10. The extractor 12 consists of a lever pivoted about 11. The hooked end 12' of said lever 12 engages the cartridge and its tail 12'' rests upon hub 32. Since lever 12 is elastic and hub 32 is formed with two

depressions 29—30, during the angular motion of the locking bar 15 said hub presents its depression 29 in a position so as to exert no pressure on the tail 12" of lever 12. The latter no longer being under stress, leaves the cartridge free to be expelled from the ejector which in the meanwhile is hit by the projection 17, as indicated above (see Figure 4). When, on the contrary, the tail 12" of lever 12 finds itself in the depression 30, hook 12' of lever 12 is not under stress and it allows the cartridge to be engaged by the extractor hook. In all other positions of the locking bar 15 the end portion 12" of lever 12 is maintained rigidly against hub 32 particularly when such lever 12 acts to draw out the cartridge case and to insert a fresh cartridge into the barrel. The figures show the breechblock in particular positions, and thus do not show the frictional contact between 12" and 32.

The hub 32 is provided with a cylindrical part 31 and two substantially diametrical depressions 29 and 30. When the smooth projection 12" of the extractor rests upon the depressions 29 or 30, the extractor 12 is subject to play and its hook 12' consequently engages the cartridge case rim lightly. However, when the smooth projection 12" of the extractor rests upon the cylindrical part of the locking bar hub 32, the free play in the extractor is temporarily inactive and in such condition the hook 12' firmly engages the cartridge case rim. During forward movement of the breechblock the extractor 12 also remains rigid since the projection 12" rests on the hub 32 while the tooth 12' prevents the cartridge cap from contacting the firing pin 28.

The depressions 29 and 30 provide loose positioning of the smooth projection 12" at the completion of the backward (firing position) and forward movement (battery position after firing) of the breechblock, respectively. In the firing position the spent cartridge case is therefore readily released from the extractor by means of the action of the ejector. In the battery position, there is practically no grip upon the cartridge case rim by the hook 12'. In either position, the smooth projection 12" rests freely in either depression 29 or 30. On the other hand, the breechblock effectively secures a firm grip on the cartridge case rim by means of the extractor hook 12' during either forward or backward movement of the

breechblock since the smooth projection 12" bears upon the cylindrical part 31.

It is understood that the invention is not limited to the exact disclosure herein described but may lend itself to a variety of expressions in the scope of the appended claim. For example, in order to aid the movement of the pivot 18 in groove 19, a torsion spring may be provided around the pivot 14 to cause the locking bar 15 to shift to the position shown in Figure 1.

What I claim is:

In a semi-automatic firearm, a receiver, a trigger mechanism mounted within said receiver, a breechblock operatively connected with said trigger mechanism, a recoil spring biasing one end of said breechblock from a firing position to a battery position, said breechblock comprising a pivot, an extractor carried by said pivot and having a hooked end and another smooth projection, an ejector carried by said pivot, another pivot mounted on said breechblock intermediate its ends, a locking bar having a pivoted end carried by said second-mentioned pivot and a pivotally mounted free end, a groove formed in said receiver and engaging said pivotal free end, said pivotal free end being slidably movable vertically within said groove with respect to the longitudinal axis of said fire-arm, a projection formed on said pivoted end for maintaining said battery position of said breechblock, a hub formed on said free end for striking said ejector, said pivoted end having two depressions disposed diametrical-ly opposite each other for causing free play of said ex-tractor when said breechblock maintains said firing and battery position, and a firing pin integrally formed on said breechblock and disposed intermediate said ejector and said hooked end.
